UMBRELLA FERRULE

Louis Malin, Brooklyn, N.Y.

Application July 26, 1957, Serial No. 674,487

1 Claim. (Cl. 135—36)

This invention relates to umbrellas or parasols, and more particularly to the ferrule structures used therein on the shafts, to secure the covering material in place.

An object of the invention is to provide a novel and improved clamping ferrule construction for an umbrella or the like, by which the fabric or covering of the umbrella may be readily attached to the shaft with the employment of a minimum number of parts or components.

Another object of the invention is to provide a novel and improved clamping ferrule for an umbrella, which is so constituted and organized that it may be readily removed for reuse in the event that for some reason the initial assembly and attachment of the fabric is found to be not satisfactory.

A still further object of the invention is to provide a novel and improved ferrule construction in accordance with the above, which may be economically fabricated on high-production equipment, so as to have a low initial cost.

A feature of the invention resides in the provision of an improved ferrule and fabric clamping construction, wherein only two parts or components need be utilized to secure the fabric to the umbrella shaft.

Other features and advantages will hereinafter appear.

In the drawings accompanying this specification, similar characters of reference indicate corresponding parts wherever possible in the several views, in which:

Figure 1 is an axial sectional view, enlarged, of an improved ferrule and clamping structure made in accordance with the invention, shown as engaged with and gripping a fabric umbrella cover.

Fig. 2 is an inside end view of the ferrule and clamping structure of Fig. 1, with portions of the fabric broken away to reveal details.

Fig. 3 is an end view of the ferrule component per se, as used in Figs. 1 and 2.

Fig. 4 is a plan view of a clamping ring constituting part of the structure of Figs. 1 and 2.

Fig. 5 is an axial sectional view, enlarged, of a ferrule and clamping construction illustrating a modification of the invention.

Fig. 6 is a view of the inner end of the assemblage of Fig. 5.

Fig. 7 is a plan view of the clamping washer employed in the structures of Figs. 5 and 6.

Fig. 8 is a fragmentary axial sectional view similar in part to Fig. 1 but illustrating a further modification of the invention.

Referring first to Figs. 1—4 the improved ferrule and clamping structure shown therein comprises a ferrule component indicated generally by the numeral 10, having a flared or tapering tubular body 11 the large end of which terminates in an outwardly extending annular flange 12. Preferably, as shown in Fig. 1, the flange 12 is generally flat, lying in a transverse plane which is perpendicular to the axis of the ferrule body 11.

Cooperable with the flange 12 for the purpose of

clamping and securing a fabric or other covering 13 to the ferrule 11 and the shaft (not shown) on which the ferrule is carried, I provide a plain, flat annular member or ring 14, said ring having an outside diameter which is preferably smaller than the larger diameter of the flange 12. The inside diameter of the ring 14 is preferably larger than the small diameter of the flange 12, all as may be seen from an inspection of Fig. 1.

In accordance with this invention, for the purpose of securing the ring 14 in clamping engagement with the fabric 13 and against the flange 12, I provide in the latter a plurality of fingers 16, shown here as six in number, which are lanced from the flange and struck up, as seen in Fig. 1. The fingers 16 are shown as pointed and of triangular shape. However, it will be understood that the fingers may have any other configuration found suitable.

Referring to Fig. 3, the fingers 16 are so positioned that they may be encircled by the clamping ring 14, the said ring extending close to the outer faces of the fingers.

By making the fingers 16 pointed, I am able to apply the fabric or covering 13 easily and quickly to the flange 12, together with the ring 14 so as to cause a piercing of the fabric 13 by the fingers. This may be readily seen from an inspection of Fig. 2.

Upon the fabric 13 being applied to the flange 12 of the ferrule, and the ring 14 placed thereover with the fingers 16 projecting through the fabric, the said fingers are bent radially outward, as shown in Figs. 1 and 2, thereby causing them to overlie the ring 14 and to securely hold the same in position clamping the fabric 13 against the flange 12. The large area of contact of the ring 14 with the fabric will securely hold the latter, in conjunction with the plurality of fingers 16 which pierce the fabric. Therefore, a secure attachment of the fabric 13 to the ferrule 11 is effected, and in consequence the fabric will be held to any shaft on which the ferrule may be placed.

It will be understood that the fabric cover 13 is also centrally pierced in the zone surrounded by the ring 14, to enable the shaft of the umbrella to pass through the cover and through the ferrule body 11.

Another embodiment of the invention is illustrated in Figs. 5—7, wherein there is shown a ferrule 20 having a tapered or flared tubular body portion 21 provided at its large end with an outwardly extending plain annular flange 22.

For cooperation with the flange 22 I provide a clamping washer or ring 24 having a plurality of sharp or pointed fingers 26 extending upward from its inner peripheral portions, as seen in Fig. 7. The fingers 26 are so positioned that the flange 22 of the ferrule fits snugly within them, as illustrated in Fig. 5. In assembling this ferrule structure to the fabric or cover of the umbrella, the latter is provided with a hole or opening having a size commensurate with the inside of the flange 22 of the ferrule. The ferrule is then slipped through such opening, bringing the flange 22 thereof against the inner marginal portions of the fabric, and thereafter the ring 24 is slipped over the ferrule and the fingers 26 thereof caused to pierce and penetrate the fabric whereby they project beyond the flange 22. Thereafter the fingers 26 are folded or bent inward, as illustrated in Fig. 6, causing them to grip the flange 22, and by such operation the fabric 13 is securely clamped between the flange and the ring.

A modification of the invention is shown in Fig. 8, wherein a ferrule body 31 has a flange 32 provided with an inwardly rolled edge 32a. By such construction there is provided a rolled surface of the exterior of the ferrule, as distinguished from the thin sharp edge of the flange 12

of the ferrule 11. Otherwise, the structure of Fig. 8 is similar to that of Figs. 1-4.

The improved ferrule and clamping structure as above set forth may be advantageously constituted of sheet metal stock, although it will be understood that the invention is not limited thereto, since other suitable materials may be employed.

It will be understood from the foregoing that I have provided a novel and improved construction of ferrule and clamping means for securing the cover material of an umbrella to the shaft thereof, such means being constituted of only two components, and being simple and economical in its construction. Moreover, I have found that such means may be easily and quickly applied and assembled, and holds the umbrella cover in an effective and reliable manner at all times. If for any reason the assembly of the fabric to the ferrule structure is imperfect so that the components must be separated, the ferrule 20 may be readily reused, since it does not carry the clamping fingers.

Variations and modifications may be made within the scope of the claim, and portions of the improvements may be used without others.

I claim:

A combined ferrule and clamping structure for an umbrella or the like, comprising a tubular drawn sheet

metal ferrule body adapted to be affixed to the upper end of an umbrella shaft, said body having an enlarged, outwardly flared end and having at said end an outwardly extended single thickness flat flange part formed integral with the ferrule body; a flat clamping ring part juxtaposed and arranged broadside to said flange part; an umbrella cover interposed between said parts; and clamping means carried by and integral with the flange part, said clamping means passing through the umbrella cover, extending completely past and overlying and clamping the said ring part, thereby to securely hold the cover between the said parts with the parts disposed in adjoining parallel planes, the said ring part being constituted as a flat, planar ring and said clamping means comprising a plurality of fingers integral with the flange part, said fingers clamping against the said ring part.
